LOCKING MECHANISM FOR WINDOW LATCHES

Filed April 23, 1949

UNITED STATES PATENT OFFICE

2,613,524

LOCKING MECHANISM FOR WINDOW LATCHES

Neil O. Holmsten, New Rochelle, N. Y.

Application April 23, 1949, Serial No. 89,185

1 Claim. (Cl. 70—89)

1

This invention relates generally to latching means for swinging windows or glass doors. More specifically, the invention relates to a locking means to be used in conjunction with a pivoted latch such as is used on French windows and the like.

The invention is especially designed for application to standard type pivoted latches which are already in use for holding swinging windows and doors closed. Latches of this type are attached to the inside of a window, or door, and are quite effective for holding them closed, but it is a relatively simple matter for an unauthorized person to release the latch and open the window, or door, to which it is applied, to gain entrance to a building. It is only necessary to break a window pane or remove a small section thereof, or cut a small hole through a door, and then reach in from the outside and release the latch after which the window or door may be opened.

This invention, as disclosed herein, is adapted to be applied to either single or double swinging windows or doors, and comprises a locking lever secured to a rotatable stud which is rotatably mounted in a casing secured to a window or door jamb, and is adapted to be swung into or out of engagement with a pivoted latching member carried by a window or door jamb. A key-operated or combination locking means is provided to lock the lever in engagement with the latching member when the latching member is in latching position and thus prevent releasing the latching member by unauthorized persons.

The principal object of the invention is to provide an improved locking mechanism for application to windows or doors to be used in conjunction with standard type latching means thereon.

Another object of the invention is to provide a locking mechanism of this type, which is of simple construction, efficient in operation and which is relatively inexpensive to manufacture.

Other and more limited objects of the invention will be apparent from the following specification and the accompanying drawings forming a part thereof wherein:

Fig. 1 is a front elevation showing my improved locking mechanism applied to a pair of French windows in locking position;

Fig. 2 is a vertical section taken on the line 2—2 of Fig. 1;

Fig. 3 is a vertical section taken on the line 3—3 of Fig. 2; and

Fig. 4 is a horizontal section taken on the line 4—4 of Fig. 1.

2

The invention as illustrated herein is shown as applied to a pair of French type swinging windows which are adapted to close against a stationary jamb on which is pivotally mounted a pair of latching members, each consisting of an operating handle, adapted to be swung inwardly, and a latching finger which projects out through aligned slots in the jamb and the window pane and into engagement with the outer surface of the window frame to hold it closed against the jamb. The invention comprises a locking lever, secured intermediate its ends to a rotatable stud, which is adapted to be rotated into and out of engagement with the operating handles to control the operation thereof. A key-operated locking mechanism is provided to lock the lever in handle-engaging position.

Referring now to the drawings by reference characters the numeral 1 indicates a section of a window jamb against which a pair of swinging windows 2 are adapted to abut when closed. Each of the windows 2 consists of a frame 3 and a glass pane 4 suitably mounted therein. Latching members, generally indicated by the numeral 5, are provided for holding each of the windows 2 in closed position. Each of these latching members 5 consists of an operating handle 6 and a latching finger 7 which is formed integral therewith. Each latch 5 is pivotally mounted upon a pivot bolt 8 which is supported by inwardly extending ears 9 of a bracket 10, which is secured to the jamb 1 by screws or rivets 11. When a window 2 is in closed position abutting the outer surface of the jamb 1, the latching finger 7 is adapted to extend through a slot 12 in the jamb 1 and a slot 13 in the window frame 3 which aligns with the slot 12. The latching member 5 is mounted for movement in a plane perpendicular to the jamb 1 so that in order to unlatch the window 2 the handle 6 is pulled inwardly from the jamb 1, which draws the latching finger 7 in through the aligned slots 12 and 13 and out of engagement with the window frame 3. Reversely, in order to latch the window 2 when it is in closed position against the jamb 1, the operating handle 6 is pushed outwardly towards the jamb 1 which projects the finger 7 through the slots 12 and 13 and up into engagement with the window frame 3, as shown at 14. In order to lock the latching members in latching positions so that the fingers 7 cannot be withdrawn from engagement with the window frame 3, I provide a locking mechanism, which is generally indicated by the numeral 15. This locking mechanism comprises a lever 16 which is rigidly secured to the outer end of a

shaft 17. The shaft 17 is rotatably mounted in a bushing 18 which is secured to and extends inwardly from the cover 19 of a casing 20. The casing 20 consists of a base plate 21, the cover 19 and an annular frame 22 which is disposed between the base plate 21 and the cover 19. The base plate 21, frame 22 and cover 19 are shown as held together by screws 23 and 36. The casing 20 is secured to the inner face of the jamb 1 by non-removable screws 33 which extend through 10 apertures in the base plate 21. The shaft 17 has a reduced cylindrical end 25 and a square section 24 adjacent thereto. The square section 24 extends between the base plate 21 and the cover plate 19 within the casing 20, and the reduced end 25 extends into a recess 26 in the base plate 21. The shaft is held in position within the bushing 18 by a washer 27 which is secured to the end of the shaft 17 within the recess 26 by a screw 28. The lever 16, when in locking position, as shown in full lines in Fig. 1, is adapted to extend across the operating handles 6 and thus prevent their movement. In order to unlock the operating handles 6, the lever 16 is turned from the full line position in Fig. 1 to the dotted line position therein. In order to prevent the unauthorized turning of the lever 16 and the unlatching of the windows 2, I provide a lock 29 of the lever tumbler type which is mounted within the casing 20. The lock 29 has a locking plunger 30, shown as key-operated, which is adapted to be projected into one of the notches 31 in a disc 32 which is secured to the squared section 24 of the shaft 17 within the casing 20. In order to yieldingly hold the lever 16 in either locking or unlocking position, I provide a spring member 35 of spring wire which is mounted within the casing 20 between the cover 19 and the disc 32 and is held in position by a pair of screws 36. The free ends 37 of the spring member 35 yieldingly engage parallel sides of the squared section 24 of the shaft 17, as shown in Fig. 3 when the locking lever 16 is in either locking or unlocking position. As the lever 16, and with it the shaft 17, is turned from one position to the other, the free ends 37 of the spring will be forced outwardly by the engaging corners of the squared section 24, but will spring back into engagement with the other parallel sides of the squared section 24 as the lever 16 approaches either the locking or unlocking position, where it will be held by the spring member 35 against free movement. After the lever 16 has been locked in locking position and the locking plunger 30 of the lock 29 has been projected into a notch 31 in the disc 32, the lever 16 cannot be 50 55

turned to unlocking position until the locking plunger 30 has been withdrawn, by means of the proper key or combination, from the notch 31.

From the foregoing it will be apparent to those skilled in this art that I have provided a very simple and effective mechanism for accomplishing the objects of the invention.

It will be understood that I am not restricted to the specific construction shown and described herein, as various modifications may be made thereto within the spirit of the invention.

What is claimed is:

Locking mechanism for securing a window latch adapted to hold a swinging window closed against a jamb and having a latching finger pivoted to said jamb to engage and hold the window closed and having an operating handle mounted to swing outwardly in a plane normal to said jamb to move said finger into and out of engagement with the window, said handle when in latching position extending along said jamb and having a top surface a portion of which at least is parallel to said jamb, said locking mechanism comprising a casing to be secured to said jamb under said handle, a shaft rotatably mounted in said casing and projecting outwardly therefrom, a lever rigidly secured to the outer end of said shaft and adapted when in locking position to overlie and engage said top surface of said operating handle to prevent outward movement thereof and when in releasing position to extend parallel to said handle, a disc having a notch rigidly secured to said shaft within said casing, a lock in said casing having a plunger adapted to be inserted into said notch for securing said shaft against rotation with said lever in handle-engaging position, and spring means to align said notch with said plunger.
